DESIGN FOR A CLOSURE CAP OR SIMILAR ARTICLE

Joseph R. Fleisch, Clifton, N. J., assignor to
Anchor Cap & Closure Corporation, Long
Island City, N. Y., a corporation of New York

Application July 15, 1935, Serial No. 57,644

Term of patent 14 years

To all whom it may concern:

Be it known that I, Joseph R. Fleisch, a citizen of the United States, residing in Clifton, county of Passaic, State of New Jersey, have invented a new, original, and ornamental Design for a Closure Cap or Similar Article, of which the following is a specification, reference being had to the accompanying drawing, forming a part thereof.

The figure is a perspective view of a closure cap showing my new design.

Dominant features of the design are, a skirt of substantially the same size at top and bottom, and having an ornamentation comprising a plurality of relatively prominent grooves spaced

about the circumference of the skirt, panels intermediate the prominent grooves with groups of alternately arranged relatively narrow ribs and grooves on the panels, and plan narrow smooth portions on each side of the group of narrow ribs and grooves between said ribs and grooves and the said prominent grooves, said prominent grooves, panels, relatively narrow ribs and grooves and said smooth portions extending from the bottom edge to the top edge of the skirt.

I claim:

The ornamental design for a closure cap or similar article, substantially as shown and described.

JOSEPH R. FLEISCH.
